VACUUM CLEANER

Gustaf Einar Lofgren, Riverside, Conn., assignor
to Electrolux Corporation, Dover, Del., a cor-
poration of Delaware

Application November 29, 1935, Serial No. 52,027

15 Claims. (Cl. 183—37)

My invention relates to vacuum cleaners and more particularly to vacuum cleaners of the kind having a cleaner unit including a casing or housing enclosing a motor and a fan, a nozzle, and a tubular member including a hose for establishing communication between the casing and the nozzle, the casing being pulled by the hose on a carpet or surface.

The invention aims to provide a more efficient construction of vacuum cleaner unit both from manufacturing and operating points of view. In my novel construction, I preferably make the housing of two stampings of such character with relation to the unit that they can have endless jointing seams or edges. This provides rigidity of structure. I find that this is feasible if the housing is made of an upper deep shell and a lower shallow shell joined near the floor. Thus the joining line is below the dust bag opening and can be continuous.

An object of the invention is to utilize a minimum of structural parts. The shell is made of a minimum number of stampings and yet the housing is strong. The housing is subdivided by transverse bulkheads which serve to stiffen the shell, act as supports for the motor-fan unit, and provide pressure demarcation as well as space demarcation. Due to the construction, only the dust bag space is under suction. The enclosure for the motor and fan is under atmospheric pressure.

A further object is to provide an improved motor-fan unit, which is better protected than heretofore.

The nature of my invention will be understood from the following description taken in conjunction with the accompanying drawings forming part of this specification and of which:

Fig. 1 is a vertical longitudinal sectional view through a vacuum cleaner unit embodying the invention and also parts attached thereto;

Fig. 2 is an enlarged longitudinal sectional view, taken on line 2—2 of Fig. 4;

Fig. 3 is a transverse sectional view taken on the line 3—3 of Fig. 1;

Fig. 4 is a transverse sectional view taken on the line 4—4 of Fig. 1;

Fig. 5 is a horizontal sectional view taken on the line 5—5 of Fig. 1;

Fig. 6 is a sectional view taken on the line 6—6 of Fig. 4;

Fig. 7 is a sectional view taken on the line 7—7 of Fig. 4;

Fig. 8 is a cross-sectional view of a portion of a vacuum cleaner in accordance with my invention,

including a dust indicator, and shows the handle and switch arrangement more in detail; and

Fig. 9 is a cross-sectional view taken on the line 9—9 of Fig. 8.

The vacuum cleaner includes a cleaner unit 10 to which is connected a flexible hose 11, by which the cleaner unit may be pulled by the operator, and a hollow wand 12 to which is connected the nozzle 13. This general type of cleaner and its mode of use are known. The cleaner unit to which the present invention is directed, rests on the floor. The operator generally holds the wand 12 with the flexible hose loose between the cleaner unit and the wand.

The cleaner unit 10 includes a housing made essentially of an upper shell 15 and a lower shell 16. Preferably the shells are made from flat sheet metal stock by die forming in a punch press. The lower shell is shallow and is formed with ridges 17 on the under sides to act as runners 18 when pulling the cleaner unit on the carpet or floor. The lower shell has a continuous or endless top edge at 19, which, when the cleaner unit is resting normally, is in a horizontal plane. The upper shell 15 is a deep drawn shell which is a sort of inverted dish and which also has a continuous or endless edge 19. When the cleaner unit is resting normally, the edge 19 is likewise in a horizontal plane. The edges 18 and 19 are joined as by welding. Both the upper and lower shells preferably widen from the center-line to the jointure so that the plane of joining is at the horizontal cross-section of maximum area. The plane of joining is close to the floor.

At the forward end of the cleaner unit is a cover 20 which controls access to the dust bag 21 and to which the hose 11 is connected by a suitable coupling member 22.

The housing of the cleaner unit is subdivided by two partitions or bulkheads 25 and 30. Bulkhead 25 may be termed the forward bulkhead and bulkhead 30 the rear bulkhead. Each of the bulkheads is flanged around its periphery and welded to the shell all the way around to form an air-tight joint. The bulkheads divide the housing into three distinct compartments, namely—a dust compartment 26, a motor-fan compartment 27, and a filter compartment 28. The bulkheads are imperforate except for center openings 31 and 32.

Positioned in opening 31 is a motor-fan unit 50 suspension ring 33, preferably made of rubber. Ring 33 also extends within a metal ring 34 secured to a case 35 for the motor-fan unit. A cap ring 36 is placed over ring 33 and held in place by a member 37 fastened to the bulkhead 55

as by a screw, as shown. A spacer ring 38 may be used between ring 34 and the center flange 39 of bulkhead 25.

The other or exhaust end of the motor-fan unit is similarly supported by means of a rubber cushioning ring 41 mounted in the central opening 32 of bulkhead 30. A seating ring 42 holds ring 41 in place. This ring is fastened to bulkhead 30 by screws 43. Ring 41 seats in a fibre or Bakelite end cap 44 forming part of the case 35.

The bottom shell 16 is provided with an opening 45 covered by means of a removable cap 46 whereby the case 35 can be inserted and removed from the motor-fan compartment. In inserting the motor-fan unit, the case 35 is held in alignment with openings 31 and 32 and rubber rings 33 and 41 are then inserted by pushing them toward the case 35 from within compartments 26 and 28 respectively, after which the caps 36

and 42 are applied. The case 35 and the connections between the same and the bulkheads are air-tight wherefore, due to the air-tight connection of the bulkhead 25 with the shell, the only one of the compartments which is subjected to suction is compartment 26. Thus substantially one-half of the shell is relieved of stress due to preponderance of external pressure. It will be understood that the bulkheads greatly strengthen the shell.

The dust bag 21 is provided with a ring 48 which is held between cover 20 and a flange on the upper shell. Suitable mechanism may be employed to clamp cover 20 onto the housing with the dust bag ring therebetween. Clips may be used as shown in United States Patent No. 1,757,239 of May 6, 1930. The dust bag is preferably large so as to wrinkle within chamber 26 and distention of the dust bag is resisted by a plate 49 and a spring 51 attached thereto and to member 31. Member 49 may be utilized to operate a signal as disclosed in United States Patent No. 2,022,250 of November 26, 1935.

Upper shell 15 is formed with a ridge 52 at the top which is a continuation of a handle part and which provides space for dust indicating mechanism. Ridge 52 extends longitudinally and is preferably initially stamped into the upper shell.

The handle is formed as a separate piece 53. Handle part 53 overlaps and is secured to ridge 52 and is suitably secured as by screws to the shell at about the place of bulkhead 30. One preferred arrangement for securing the handle is described in detail in connection with Figs. 8 and 9. The shell may be recessed at 54 and the part 53 is cut away for grasping by the hand. The handle is above the motor-fan compartment which is at the center of gravity of the cleaner unit.

The rear end of part 53 is open at 56 for reception of the plug of an electric cord. A step switch 57 is incorporated in part 53 and includes a step button 58. The step switch can readily be connected to the motor through an opening in the shell. The step switch and contact points are removable with the part 53, for instance, as described in connection with Fig. 8.

A hole 61 is provided for access to compartment 28. This hole is normally closed by means of a cover 62 which may be made as a die casting and which includes a discharge opening 63 into which the hose 11 may be secured for blowing purposes. Compartment 28 may have a special filter pad 64 therein or may be loosely filled with filtering material.

Referring more particularly to the motor-fan

assembly, the motor is supported on two rings 44 and 65 made of Bakelite or fibre or other suitable electrical insulating material. A sheet metal cylinder 66 extends between parts 44 and 65. Mounted on part 65 are members 67 and 68. Member 68 is a stationary member between fan rotors 69 and 70. Intermediate directing vanes are mounted on member 68. The case 35 is like a can and it can be supported in any position radially.

Figs. 6 and 7 show how the motor is supported. Pins 72 and 73 extend axially from the motor casing 74. There are several pins 72 and several pins 73, disposed about the motor housing. Conical springs 75 extend between pins 73 and rings 44 and 65 and are seated in recesses in the rings. Caps 76 hold the apices of the springs in position. Caps 76 and pins 73 may be made of electrical insulating material.

Rods 78 pull the rings 44 and 65 together and members 67 and 68 are secured to ring 65 as by screws 79. The motor includes the usual armature 82 and shaft 83 carrying the fan rotors and mounted in ball bearings 81.

The operation is as follows:

The motor is set in operation by stepping on switch button 58. The motor rotates the fan and causes flow of air. The nozzle 13 is applied to the object or surface to be cleaned. Dust-laden air passes through nozzle 13, wand 12, tube 11 and through union 22 into the dust bag 21. Here the dust is deposited and cleaned air passes on through the fan and past the motor, cooling the same, and out through the filter chamber 28 where fine particles are removed which are not caught in the dust bag. The filter chamber also acts as a muffler.

Chamber 26 is under suction which may be of a value exceeding thirty inches of water lift. Consequently, the total pressure differential on the walls of chamber 26 (atmospheric pressure on the outside less suction pressure on the inside) will be high. The shell is assisted from buckling by the variations in its wall structure. The welded joint between the shells is of assistance in this respect. The ridge 52 is also advantageous in this respect. Additional ridges or reinforcements may be provided in the side walls to the extent found necessary.

With a properly air-tight case 35 and tight connections, compartment 27 will be at atmospheric pressure. This is due to the separate assembly of motor and fan and the bulkheads, as above explained. Should there be some leakage through case 35, it would not affect the relief of stress on the walls of compartment 27.

Compartment 28 is at somewhat above atmospheric pressure but the pressure is slight. This compartment is essentially free of wall stress. Thus the suction is confined to the chamber containing the dust bag, and no part of the motor or fan is positioned in this chamber.

It will be noted that the outer housing and the motor-fan case are entirely separate. The motor-fan assembly is a separate sub-assembly. All the electric parts are in one sub-assembly. This facilitates original manufacture and repairs. The generally continuous outward flare of the shells is of assistance since the shells can be nested in the process of manufacture and for shipment of parts. This also facilitates insertion of the bulkheads.

In Figs. 8 and 9, there is shown, on a somewhat enlarged scale, a portion of a cleaner similar to that shown in the preceding figures, but includ-

ing dust indicator mechanism and a removable handle and switch assembly.

Member 49, against which dust bag 21 presses when inflated, is resiliently supported by means of a plurality of conical springs 90 suitably secured thereto. The opposite ends of springs 90 engage grooves formed in the heads of bolts 91 which are threaded into bulkheads 25.

Secured within ridge 52 of upper stamping 15, preferably by welding, is a bracket 92 having apertures for receiving prongs 93 of a frame 94. Frame 94 includes a pair of spaced side bars 95, one end of each of which terminates in the prongs 93. The other ends of bars 95 are integral with a portion 96, to the free end of which is secured a spring 97. The other end of this spring is supported by a bracket 98 welded within ridge 52. Spring 97 holds portion 96 against a projection 99 secured within the casing and the slight inclination of the spring urges the entire frame 94 to the right, as viewed in Fig. 8, and maintains the ends of prongs 93 in contact with the interior of the casing. Thus, the frame is held securely in place.

Extending between the side bars 95 are shafts 100 and 101. Rotatably mounted on shaft 100 is a bell crank lever 102 having arms 103 and 104. The end of arm 103 contacts the central portion of member 49 and consequently movement of member 49 to the right, as viewed in Fig. 8, causes bell crank lever 102 to pivot in a counter-clockwise direction about shaft 100. A spring 105 encircles shaft 100 and has one end in engagement with frame 94, and the other end in engagement with the under side of arm 104, thereby tending to rotate the bell crank lever 102 clockwise and maintaining the end of arm 103 in contact with member 49. The end of arm 104 is provided with a rack 106 which engages a gear 107 mounted on shaft 101. Rotatable with gear 107 is a sector 108 constituting a visual indicator. For instance, one part of the outer surface of sector 108 may be red, as indicated at 109, while the other part 110 may be white. An air-tight window 111 is set in the casing above sector 108 so that the position of the latter may be seen therethrough. A pin 112 limits the movement of bell crank 102 in clockwise direction.

It will be seen that all of the dust indicator mechanism, with the exception of arm 103, is contained within the space within ridge 52. It is thus entirely out of the way of the dust bag and does not interfere with the expansion of the latter.

The operation of the dust indicator will be largely apparent. As dust accumulates within bag 21, it reduces the flow of air through the walls of the bag, thus increasing the pressure drop therethrough. This causes the bag to exert more force against member 49, thus moving this member to the right, as viewed in Fig. 8 against the force of springs 90. Bell crank 103 is thereby pivoted counter-clockwise and rotates gear 107 and sector 108 in a clockwise direction, thus bringing the red portion 109 into view through window 111. This is an indication to the operator that sufficient dust has been collected in the bag to make the emptying thereof desirable.

Handle 53 includes an end portion 115 which extends over and conforms generally to the outer contour of the higher end of ridge 52. Portion 115 is formed with an opening 116 in registry with window 111. A cylinder 117 is secured by means of a strap 118 to the outer end of ridge 52. Strap 75 118 may be welded to the casing and to the

cylinder. Received within cylinder 117 are two buttons 119 having outer ends 120 of reduced diameter. A spring 121 tends to force buttons 119 outwardly. Portion 115 of the handle is formed with skirts 122, which extend down to the top of stamping 15, and which are formed with apertures for receiving the ends 120 of the buttons. Thus, the forward end of the handle is removably secured to the casing.

The other end of the handle is formed with a recess in which is positioned the step switch assembly 57. This assembly includes the usual chassis 125 of insulating material in which is mounted a snap switch mechanism 126 and electric contact pins 127 positioned in opening 56. A step button 58 is reciprocably mounted in a recess 129 in the chassis and is urged upwardly by a spring 130. Upward movement of the button is limited by a flange thereon contacting the top of the handle stamping. A pin 131 is pivoted on button 128 and is arranged to engage notches, formed in one end of a pivotally mounted switch arm, when the button is depressed in order to throw the switch to the opposite position. An opening 133 is formed in the upper part of stamping 15 between bulkheads 25 and 30 and consequently communicates with motor-fan compartment 27. The electric leads from the motor within case 35 may be thus connected to binding screws 134. Inasmuch as atmospheric pressure prevails at all times within compartment 27, there is no necessity for sealing opening 133.

A bracket 135 is welded to the top of stamping 15 and extends between the switch chassis 125 and a portion 136 of the handle stamping. A screw 137 passes through openings formed in portion 136 and bracket 135 and has threaded engagement with chassis 125, thus securing the rear end of the handle to the casing and holding the switch assembly rigidly in place. A sleeve 138 fits snugly within the opening 56 in the rear portion of the handle stamping and surrounds contact pins 127. A member 139 is welded to stamping 15 and a screw passes through sleeve 138 and has threaded engagement with member 138. Thus, sleeve 138 is secured in place which, by virtue of its close fit in opening 56, gives additional support to the rear of the handle.

It will be seen that the handle and switch assembly may be installed or removed as a unit. Removal, for instance, may be accomplished by unscrewing screws 137 and 140 and by pressing in buttons 119 until the ends 120 thereof are disengaged from the handle. The motor leads are still attached to the switch, but sufficient slack may be provided in the leads so that the handle and switch may be removed far enough to give access to screws 134.

While, in the foregoing, I have described a more or less specific embodiment of my invention, it is to be understood that this has been done for purposes of illustration only, and that the scope of my invention is not to be limited in any manner thereby, but is to be interpreted as broadly as is commensurate with the appended claims when considered in relation to the prior art.

What I claim is:

1. A vacuum cleaner unit including a casing, said casing being horizontally elongated, a motor, 70 fan and dust separator in said casing in horizontal alignment, said casing having an air inlet and an air outlet, and said casing including upper and lower shells having mating edges, each of said shells being essentially formed as sheet 75

4

metal pans having their widest portions at the mating edges, the lower shell having elongated depressions therein extending below the remainder of the lower shell to form runners.

5 2. A vacuum cleaner unit including a casing, said casing being horizontally elongated, a motor, fan and dust separator in said casing in horizontal alignment, said casing having an air inlet and an air outlet and an air inlet, and said 10 casing including a deep upper arched shell and a shallow lower shell, said shells having mating edges, each of said shells being essentially formed as pans having their widest portions at the mating edges, said upper shell being arched both 15 longitudinally and transversely.

15 3. A vacuum cleaner unit including a casing, said casing being horizontally elongated, said casing having an air inlet and an air outlet, said casing including an upper deep shell arched both 20 longitudinally and transversely and a shallow bottom shell joined to said upper shell in a continuous joint below said inlet and outlet, said shell widening to the joint, interior vertical transverse bulkheads in said casing providing a separator chamber and a motor chamber and a rear 25 chamber, a motor unit mounted on said bulkheads in said motor chamber, and an opening in said bottom shell providing access to said motor chamber.

30 4. A vacuum cleaner unit including a casing, said casing being horizontally elongated, said casing having an air inlet and an air outlet, said casing including an upper deep shell arched both 35 longitudinally and transversely and a shallow bottom shell joined to said upper shell in a continuous joint below said inlet and outlet, said shell widening to the joint, interior vertical transverse bulkheads in said casing providing a separator chamber and a motor chamber and a rear 40 chamber, and a motor unit mounted on said bulkheads in said motor chamber.

45 5. A vacuum cleaner unit including a casing, said casing being horizontally elongated, said casing having an air inlet and an air outlet, said casing including an upper deep shell arched both 50 longitudinally and transversely and a shallow bottom shell joined to said upper shell in a continuous joint below said inlet and outlet, said shell widening to the joint, interior vertical transverse bulkheads in said casing providing a separator chamber and a motor chamber and a rear 55 chamber, said bulkheads being air-tight except for interior openings, a motor housing mounted on said bulkheads in said motor chamber and having inlet and outlet openings in registry with the bulkhead openings, a motor-fan unit in said housing, and an opening in said bottom shell providing access to said motor chamber.

60 6. A vacuum cleaner unit including a casing, said casing being horizontally elongated, said casing having an air inlet and an air outlet, said casing including an upper deep shell arched both 65 longitudinally and transversely and a shallow bottom shell joined to said upper shell in a continuous joint below said inlet and outlet, said shell widening to the joint, interior vertical transverse bulkheads in said casing providing a separator chamber and a motor chamber and a rear 70 chamber, a motor unit mounted on said bulkheads in said motor chamber, said upper shell being so formed that the separator chamber is higher than the motor chamber, and a handle member above said motor chamber.

7. A vacuum cleaner unit including a casing,

said casing being horizontally elongated, said casing having an air inlet and an air outlet, said casing including an upper deep shell arched both 5 longitudinally and transversely and a shallow bottom shell joined to said upper shell in a continuous joint below said inlet and outlet, said shell widening to the joint, interior vertical transverse bulkheads in said casing providing a separator chamber and a motor chamber and a rear 10 chamber, a motor unit in said motor chamber, said upper shell being so formed that the separator chamber is higher than the motor chamber, a handle member secured to said shell and extending above said motor chamber, said handle having a hollow portion, and a switch member 15 in said hollow portion.

8. A vacuum cleaner unit including a casing, said casing being horizontally elongated, said casing having an air inlet and an air outlet, said casing including an upper deep shell arched both 20 longitudinally and transversely and a shallow bottom shell joined to said upper shell in a continuous joint below said inlet and outlet, said shell widening to the joint, interior vertical transverse bulkheads in said casing providing a separator 25 chamber and a motor chamber and a rear chamber, a motor unit mounted on said bulkheads in said motor chamber, ridges in said bottom shell forming runners, an upwardly extending ridge in the portion of said upper shell above 30 said separator chamber, and a handle member above said motor chamber in longitudinal alignment with and secured at one end to said ridge.

9. In a vacuum cleaner, an elongated casing having an air inlet in one end and an air outlet 35 in the other end, transverse bulkheads in said casing having air openings, said bulkheads being air-tight with respect to said casing and providing a chamber therebetween, an air-tight housing in 40 said chamber having end openings in air-tight registry with the openings in said bulkheads, said housing being mounted on said bulkheads, and a motor-fan unit mounted in said housing, whereby the walls of said chamber are unaffected by 45 air pressure difference caused by said motor-fan unit.

10. In a vacuum cleaner, an elongated non-circular casing, a pair of spaced transverse partitions disposed within said casing and secured in air-tight relation therewith to provide separate 50 compartments within said casing capable of sustaining different pressures, a motor-fan unit supported from said partitions in the central compartment therebetween and arranged to produce a sub-atmospheric pressure in one of the other 55 compartments, said partitions serving to strengthen said non-circular casing against atmospheric force acting on the exterior of said other compartment, and a dust separating member disposed in said other compartment in the 60 path of air flow therethrough.

11. In a vacuum cleaner, an elongated non-circular casing, a pair of spaced transverse partitions disposed within said casing and secured in air-tight relation therewith to provide separate 65 central and end compartments within said casing capable of sustaining different pressures, a motor-fan unit supported from said partitions in said central compartment and arranged to produce sub-atmospheric pressure in one of said end 70 compartments and to produce pressure higher than atmospheric in the other of said end compartments, said partitions serving to reinforce said non-circular casing against atmospheric pressure acting on the exterior of said one end com- 75

- partment and against internal pressure acting on said other end compartment, and a dust separating member in said one end compartment disposed in the path of flow of air therethrough.
5. 12. In a vacuum cleaner, an elongated non-circular casing formed with an inlet opening at one end and an outlet opening at the other, a pair of spaced transverse partitions disposed within said casing and secured in airtight relation thereto to provide separate central and end compartments, each partition being formed with an opening therethrough, a motor-fan unit including an airtight case having an intake opening at one end and an exhaust opening at the other end, said unit being supported between said partitions in said central compartment with the intake opening sealed to the opening in the partition adjacent to the end compartment communicating with the inlet opening in the casing and with the exhaust opening sealed to the opening in the other partition, whereby atmospheric pressure exists within said central compartment and said motor-fan unit is capable of maintaining subatmospheric pressure in the first mentioned end compartment and of maintaining pressure higher than atmospheric in said other end compartment, said partitions serving to strengthen said non-circular casing against atmospheric pressure acting on the exterior of said first mentioned end compartment and against internal pressure acting on the interior of said other compartment, and a dust separating member in said first mentioned compartment in the path of air flow from the inlet opening of said casing 35 to the intake opening of said motor-fan unit.
13. A vacuum cleaner as defined in claim 12 having the casing formed with an aperture communicating with said central compartment through which insertion and removal of said
- motor-fan unit may be effected, and a closure member for said aperture.
14. In a vacuum cleaner, a hollow casing, a pair of spaced partitions secured in said casing and defining a motor chamber, a motor-fan unit in said chamber having an inlet opening and an outlet opening, each of said partitions being formed with an opening, means for connecting said inlet opening to the opening in one partition and means for connecting said outlet opening to the opening in the other partition whereby atmospheric pressure may exist in said chamber, an electric switch mounted on said casing, said casing being formed with an aperture therethrough into said chamber, and electric conductors extending through said aperture for connecting said switch in the motor circuit.
15. In a vacuum cleaner, a hollow casing having flattened wall portions, a pair of spaced bulkheads secured in said casing for defining a motor chamber and for reinforcing said casing, a motor-fan unit in said chamber having an inlet opening and an outlet opening, each of said bulkheads being formed with an opening, means for connecting said inlet opening to the opening in one bulkhead and means for connecting said outlet opening to the opening in the other bulkhead, whereby atmospheric pressure may exist in said chamber, an electric switch adapted to be operated by downwardly directed foot pressure mounted on the exterior of the upper part of said casing in the neighborhood of one of said bulkheads, whereby the bulkhead prevents deformation of said casing by excessive foot pressure, said casing being formed with an aperture therethrough into said chamber, and electric conductors extending through said aperture for connecting said switch in the motor circuit.
